UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed March 1, 1926. Serial No. 91,292.

This invention relates to car roofs of the flexible outside metal type wherein like gage roofing sheets are loosely secured to the car and to each other in a manner adapted to permit relative movement of said roof sheets to a limited extent so as to be able to accommodate themselves to the distortions of the car body.

The principal object of the present invention is an improved seam construction that will permit a limited sliding movement of the roof sheets transversely of the seam and will secure a limited pivotal or sluing movement of said sheets in all positions of their sliding movement. Other objects are simplicity of construction, compactness and economy of design, fewness of parts and easy assembly.

The invention consists of principally in shaping and arranging the cooperating portions of the seam covers and the roof sheets so that the sheets are slideable crosswise to said seam cover and are adapted to pivot thereon in any position of their sliding movement. The invention further consists in the parts and in the arrangements and combinations of parts hereinafter described and claimed.

In the accompanying drawing which forms part of the specification and wherein like symbols refer to like parts wherever they occur,

Fig. 1 is a plan view of a portion of flexible outside metal car roof embodying my invention;

Fig. 2 is a vertical cross-section through one of the transverse seams on line 2—2 of Fig. 1;

Fig. 3 is a vertical cross-section through the eaves portion of the car on a line 3—3 in Fig. 1;

Fig. 4 is a vertical cross-section through the ridge portion of the car midway of adjacent transverse seams on the line 4—4 in Fig. 1;

Fig. 5 is a similar cross-sectional view on the line 5—5 in Fig. 1; and

Fig. 6 is a plan view the middle portions of the ridge ends of adjacent sheets, showing the grooves that receive the transverse-extending ribs of the ridge seam covers.

Referring to the accompanying drawing, my invention is shown applied to a car having wooden roof sheathing 7 supported on side plates 8 and a ridge pole 9. Metal roof

sheets 10 are arranged on the roof sheathing 7 side by side in two rows on opposite sides of the ridge, the two rows of roof sheets being spaced apart at the ridge, and the sheets in each row being spaced apart 60 at their sides. The roof sheets on opposite sides of the ridge are arranged in alignment transversely of the car; and mullions 11 or battens are secured to the car in the spaces between the side margins of the sheets. 65 These mullions extend transversely of the car from eaves to eaves thereof and are of less width than the spaces between the side margins of the sheets so as to permit a limited angular movement of the sheets between mullions. 70

The ridge and side margins of the roof sheets are turned up and are thence bent inwardly over the body portions of the sheets and thence downwardly to form up-standing side and ridge seam flanges or hollow ribs 12 and 13 of substantially C-shaped section. The eaves ends of the roof sheets are doubled-under to form hook flanges 14 that loosely engage the doubled-over hook 80 flanges 15^a of angle flashing strips 15 secured to the eaves of the car, such arrangement serving to loosely retain the sheets at the eaves.

The adjacent side seam flanges 12 of the 85 sheets, together with the mullions 11 located therebetween, are covered by inverted channel-shaped transverse or side seam covers or caps 16 that extend from eaves to ridge and rest on said battens. The side walls of the 90 side seam covers 16 have inwardly and upwardly extending hooked flanges 17 that interlock with the side seam flanges 12 of the sheets. The eaves ends of the side seam covers 16 are loosely held in position by extensions 16^a that are turned down over the eaves and ends of the mullions and are thence turned under the eaves corners of the roof sheets and hooked into the doubled-back flanges 15^a of the eaves flashing strips 100 15.

Pressed metal seam ridge covers or caps 18 of substantially inverted channel-shaped section straddle the spaced ridge flanges 13 of adjacent sheets and have outstanding base 105 flanges 18^a that rest on the body portions of said sheets inside the ridge and side seam flanges thereof. The adjacent ends of the ridge seam covers 18 and the transverse seam covers 16 are held in position on the 110

car by means of the usual four-way corner caps 19 that are secured in position by means of vertical bolts 20^a, which serve also to secure the running board saddles (not shown) in position.

The inverted channel-shaped ridge seam covers 18 are provided midway of their length with inwardly projecting ribs 18^b that extend transversely of the tops or web portions of said ridge seam covers and from top to bottom of their side walls. The portion of the ribs that depends from the top of each ridge seam cover, seats in grooves 20 provided therefor in the tops of the opposing ridge seam flanges 13 of the roof sheets. These grooves extend transversely of the spaced ridge seam flanges from side to side thereof midway of their length and are made wider at their ends than at their middle preferably by bowing their opposing side walls outwardly from end to end of said grooves to form reversely curved or convex surfaces 21. The width of the grooves 20 midway of their length correspond to the width of the transverse rib 19 of the ridge seam covers, whereby said ribs have a seam, fit in said groove midway of their length and are normally spaced therefrom at their ends.

By the arrangement described, the ridge ends of the sheets are properly centered between the adjacent roof mullions by the rib and groove connections between the ridge seam covers and roof sheets, and said sheets are adapted to accommodate themselves automatically to the distortions of the car body by sliding towards and away from each other along the transverse ribs of the ridge seam covers and by rocking upon the inwardly extending ribs of the ridge seam covers. An important advantage of the above arrangement is that it secures a sluing or pivotal movement of the sheets around points located in the region of the middle of their ridge ends in all positions of their sliding movement. It is noted that the portions of the transverse ribs located in the side walls of the ridge seam covers serve to limit the contact between the ridge seam flanges and the side walls of the ridge seam covers to the middle portions thereof, thereby permitting the roof sheets to slue upon the substructure when reaching the end of their outward sliding movement. If desired, these downward extensions of the transverse ribs of the ridge seam covers may be omitted and the width of the middle portions of the seam covers made reduced by providing said caps with side walls that diverge from each other from the middle of the cap to its ends.

The construction hereinbefore described permits of considerable variation without departing from my invention and I do not wish to be limited to the details of such construction.

What I claim is:

1. A flexible car roof comprising roof sheets arranged on the car side by side, a seam cover covering the adjacent margins of said sheets, and a sliding and pivotal connection between said seam cover and each of said roof sheets, said connection preventing bodily movement of the sheets lengthwise of said seam cover. 70

2. A flexible car roof comprising roof sheets arranged on the car side by side, a seam cover covering the adjacent margins of said sheets, and a connection between said seam cover and each of said roof sheets permitting independent sliding movement of said roof sheets transversely of said seam cover, said connection preventing sliding movement of said sheets longitudinally of said seam cover. 75 80

3. A flexible car roof comprising roof sheets arranged on the car side by side, a seam cover covering the adjacent margins of said sheets, and a connection between said seam cover and each of said roof sheets permitting independent sliding movement of said roof sheets transversely of said seam cover, said connection permitting independent sluing movement of said sheets around points located in the region of their adjacent margins while preventing sliding movement of said sheets longitudinally of said seam cover. 90 95

4. A flexible car roof comprising roof sheets arranged on the car side by side, a seam cover covering the adjacent margins of said sheets, and tongue and groove connections between said sheets and said seam covers permitting independent sliding movement of said sheets transversely of said seam cover. 100 105

5. A flexible car roof comprising roof sheets arranged on the car side by side, a seam cover covering the adjacent margins of said sheets, and tongue and groove connections between said sheets and said seam covers permitting independent sliding movement of said sheets transversely of said seam cover, the contact between the sheets of said tongue and groove connections being limited to points midway of their length, thereby permitting independent sluing movement of said sheets relative to said seam cover. 110 115

6. A flexible car roof comprising roof sheets arranged on the car side by side and provided along their adjacent margins with upstanding seam flanges, a seam cover covering the adjacent seam flanges of said sheets, and sliding connections between said seam cover and said seam flanges, said connections permitting sliding movement of the sheets crosswise of the car and preventing bodily movement of the adjacent ends of said sheets longitudinally of said seam cover. 120 125

7. A flexible car roof comprising roof 130

5 sheets arranged on the car side by side and provided along their adjacent margins with upstanding seam flanges, a seam cover secured to the car and covering said seam flanges, and connections between said seam flanges and said seam cover, said connections being shaped and arranged to permit sliding movement of the sheets crosswise of the seam cover and sluing movement of said sheets 10 relative to said seam cover in substantially all positions of their sliding movement.

15 8. A flexible car roof comprising roof sheets arranged on the car side by side and provided along their adjacent margins with upstanding seam flanges, a seam cover covering said adjacent seam flanges, said seam cover having a rib extending crosswise thereof and engaging a groove provided therefor in each of said adjacent seam 20 flanges.

25 9. A flexible car roof comprising roof sheets arranged on the car side by side and provided along their adjacent margins with upstanding ribs, a seam cover secured to the car and straddling said ribs, said seam cover having a rib extending transversely thereof, and said roof sheet ribs having grooves extending transversely thereof and engaging said seam cover rib, whereby said sheets 30 are adapted for independent sliding movement towards and away from each other crosswise of said seam cover, the grooves in said roof sheet ribs being wider at their ends than at their middle, thereby permit-

ting independent rocking movement of the 35 sheets on said seam cover ribs.

10. A flexible car roof comprising roof sheets arranged on the car side by side and provided along their adjacent margins with upstanding seam flanges, a seam cover 40 straddling the adjacent seam flanges of said sheets and having tongue and groove connections with said flanges that permit sliding movement of said sheets crosswise of said seam cover and sluing movement of 45 said sheets in substantially all positions of their sliding movement.

11. A seam cover for a car roof, said seam cover being of substantially channel shaped cross-section and having an inwardly projecting rib extending transversely thereof. 50

12. A seam cover for a car roof, said seam cover being of substantially channel shaped cross-section and having an inwardly projecting rib extending transversely of its web 55 and side flanges.

13. A car roof sheet having a seam flange at one margin and an upwardly opening groove extending transversely across the top of said flange. 60

14. A car roof sheet having an upstanding rib at one margin and a groove extending transversely of said rib, said groove being wider at its ends than at its middle. 65

Signed at New Kensington, Pa., this 20th day of Feb., 1926. 65

CHARLES DAVID BONSALL.
